SWITCHING MECHANISM

Juan Wenk, Madrid, Spain, assignor to Landis & Gyr, A-G., of Zug, Switzerland, a Corporation of Switzerland

Application June 18, 1930, Serial No. 462,010, and in Switzerland June 27, 1929

3 Claims. (Cl. 200—122)

The present invention relates to automatic switches and more particularly to switches which are adapted to be controlled by temperature responsive elements.

5 Objects and advantages of the invention will be set forth in part hereinafter and in part will be obvious herefrom, or may be learned by practice with the invention, the same being realized and attained by means of the instrumentalities 10 and combinations pointed out in the appended claims.

The invention consists in the novel parts, constructions, arrangements, combinations and improvements herein shown and described.

15 The accompanying drawing, referred to herein and constituting a part hereof, illustrates one embodiment of the invention, and together with the description, serves to explain the principles of the invention.

20 Of the drawing:

Figure 1 is a front elevation of the present preferred and illustrative embodiment of the invention; and

25 Figure 2 is a side elevation of the embodiment shown in Figure 1.

The present invention has for its object the provision of a simple, rugged and compact automatic switching mechanism capable of carrying relatively heavy loads. The invention further 30 provides an automatic switching mechanism which requires only a very small amount of energy for its operation.

In accordance with the present invention, the 35 automatic switching mechanism comprises a series of stationary contact members, a series of movable contact members adapted to be moved into and out of contact with the stationary series of contacts to open and close the electric circuit with which the switching mechanism is 40 employed, and thermally responsive means which move the movable series of contacts, means also being preferably provided for heating the thermally responsive means. As embodied, the movable contacts are adapted to be moved away from the stationary contacts by means of lever mechanism which is actuated by a bimetal spring, normally holding the lever in contact closing position but moving the contacts to open circuit 45 position when the spring is heated, a transformer being preferably provided and directly connected with the bimetal spring to heat the spring.

50 It will be understood that the foregoing general description and the following detailed description as well are exemplary and explanatory of the invention but are not restricted thereon.

Referring now in detail to the present preferred embodiment of the invention as illustrated in the accompanying drawing, the switching mechanism comprises a series of stationary contact 10 and a series of movable contacts 11 mounted at the ends of springs 12 which normally move the movable contacts to circuit-closing position and into contact with the stationary contacts 10, all of the contacts being mounted on an insulating base 13 which is supported 15 within the casing and on the back portion 14 of the casing. For moving the contacts 11 into and out of contact with the stationary contacts 10, a bar 15 of insulating material extends between the two series of contacts and is pivotally mounted by means of the turned down ends 16 of the cross bar 17 on which bar 15 is mounted, the ends 16 being pivoted in the small lugs 18 mounted on the insulating base 13. One of the ends of the cross bar 17 is also provided 20 with a forwardly extending portion 19 to which is rigidly fastened an upwardly extending lever 20 which connects the switch operating bar 15 with the switch actuating mechanism, to be 25 described.

As embodied, the switch actuating mechanism 30 preferably comprises a segment 22 rotatably mounted near the top of the casing by means of a short shaft 23 which is rotatably journaled at either end in brackets 24 securely fastened to the 35 casing, the segment being held fast on shaft 23 by means of set screw 25. At either end shaft 23 is formed with shoulders to limit the endwise movement of the shaft. Segment 22 is connected 40 with switch operating lever 20 by means of a pin 26 extending to one side of the segment and engaging and fitting within the bent upper end portion 27 of the operating lever 20, so that motion of the segment will be transmitted to the 45 lever. For moving the segment, a pair of bimetal springs 28 are provided, which are preferably of spiral form, and have their inner ends secured to the shaft 23, while their outer ends are fastened to connectors 29 mounted on a small block 30 of insulating material near the upper portion 50 of the casing, so that the springs are connected together in series by the shaft 23 which is of 55 conducting material.

While the bimetal springs 28 may be heated 60 either directly or indirectly, they are preferably heated directly by passing an electric current through them, and as shown in the drawing, 65 springs 28 are connected with the secondary of a small transformer 35, also mounted on the back 70 portion of the casing 14, and having its secondary 75

110

leads 21 connected with the connectors 20. The primary leads 22 of the transformer are connected with suitable terminals in the terminal connection 23 which also contains other terminals connecting with the switch contacts 10 and 11.

The switch contacts 10 and 11 are mounted in a housing 12 which is a part of the casing and may be of any desired construction.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

The switch contacts 10 and 11 are normally held in their respective positions by means of a coil spring 13 which is wound around the switch contacts 10 and 11.

the invention and without sacrificing the great advantages.

What I claim is:—

1. Switching mechanism including in combination a stationary contact, a movable contact for normally holding said contacts in closed position, a pivoted member for moving said contacts from closed position, a bimetal spiral spring connected with said pivoted member to move the movable contact from its normal position.

2. Switching mechanism including in combination stationary and movable contacts, a pivoted member for holding said contacts in closed position, a bimetal spiral spring connected in series and having their inner ends connected to said movable contact, and an otherwise connection said member to said movable contact.

3. Switching mechanism including in combination stationary and movable contacts, a pivoted member for holding said contacts in closed position, a bimetal spiral spring connected in series and having their inner ends connected to said movable contact, and an otherwise connection said member to said movable contact.

JUAN W. BELLING
